UNITED STATES PATENT OFFICE.

THOMAS BEASLEY, OF NORTH VANCOUVER, BRITISH COLUMBIA, CANADA.

COLLAPSIBLE CASE.

1,224,833.

Specification of Letters Patent.

Patented May 1, 1917.

Application filed November 22, 1915. Serial No. 62,900.

To all whom it may concern:

Be it known that I, THOMAS BEASLEY, a citizen of Canada, residing at North Vancouver, in the Province of British Columbia and Dominion of Canada, have invented new and useful Improvements in Collapsible Cases, of which the following is a specification.

This invention relates to folding boxes and has for its primary object to simplify generally the construction of foldable structures.

A further object of the invention is to provide a folding box capable of being quickly and easily assembled for use, and which, when in set up position, provides a maximum amount of space in which goods may be packed for shipment or storage, and yet which, when not in use, may be collapsed to occupy but little room.

Still further objects of the invention reside in the simplicity of construction and the attendant cheapness of manufacture; the durability of the various parts of the box; and the positive means for securing the box sections in assembled position.

With these objects in view, together with others which will appear as the description proceeds, the invention resides in the novel combination and arrangement of parts, all as will be described more in detail hereinafter and pointed out particularly in the claim.

The invention will be better understood by reference to the accompanying drawings, wherein:

Figure 1 is a perspective view of a collapsible box constructed in accordance with my invention, the same being shown in set up or assembled position.

Fig. 2 is a longitudinal section through the box.

Fig. 3 is a transverse section taken on the line 3—3 of Fig. 2.

Fig. 4 is an end view of the box when in collapsed or knock down form.

Referring now more particularly to the drawings, 5, 6, 7, 8, 9 and 10 indicate respectively the bottom, top, side and end sections of the improved box. The material of which these sections are constructed may be of metal, wood, or of such other material as may be desired or necessary, depending upon the uses for which the box is designed, but for most purposes wood will be found most practicable.

To one edge of the bottom 5 is hingedly connected the side 7, in such manner that when properly folded at right angles to the bottom, the adjacent edge of the side 7 will rest upon the bottom with the outer surface of the side flush with the lateral edge of the said bottom.

The opposite side section 8 is in a like manner connected to the bottom 5 adjacent the opposite lateral edge thereof excepting that the hinge members are for a purpose to be more fully detailed, arranged upon the inner faces of the side and bottom.

The top 6 is hingedly connected to the upper edge of the side section 7, to overlie the same and to inclose or cover the corresponding edge of the opposite side section 8, while the ends are similarly hinged adjacent one edge to the opposite ends of the side section 8, each being of such dimensions as will permit of their edges being covered or inclosed by the extreme ends of the bottom, sides and top sections.

The hinges employed in the construction of my improved box are so arranged as to permit of considerable flexibility of the various sections with respect to each other in order to enable the same to be properly arranged in set up or knock down positions, and to this end, leaves or straps 11 and 12 are secured upon the surface of the various sections and are connected through loops or sockets 13 formed or provided thereon with links 14. The straps on some of said sections are positioned with their loops slightly protruding beyond the edges thereof, while the strap or leaf on the adjacent section is spaced inwardly from the extreme edge and it will be observed from this construction that considerable play between the sections is permitted to allow the free movement of the various sections for compact arrangement of parts when the box is in knock down position. The side section 8 is hingedly connected with the bottom 5 upon the interior surfaces of both sections in order to permit of the said side folding inwardly upon the bottom when collapsing.

For securing the sections positively in set up position, each end of the box is provided with a stem or shank 15 protruding slightly beyond the edge thereof and adapted to extend through an opening 16 provided in the surface of the adjacent box section. The stem or shank may be threaded as shown for the reception of a nut 17 for

securely holding the sections together. Each end is preferably provided with two of such stems, one adapted to protrude through openings in the side member 7, while the 5 other engages within an opening formed in the top 6. The side section 8 is also provided with a stem for engagement within an opening or aperture formed in the adjacent surface of the top 6. This construction 10 obviously permits of the various box sections being securely held together.

Each of the bottom, top, and side sections is provided with a transversely extending brace member 18, the said members being 15 secured to the outer surface of each of said sections in any preferred manner. The brace members are arranged preferably one near each end of the respective sections, and for the purpose of relieving the box of 20 strains due to rough handling of the same, the said braces are positioned to provide a continuous brace extending around the box with their ends in engagement with each other. The brace members on the sides 7 25 and 8 are a trifle longer than the width of the latter, and protrude at each end beyond the lateral edges of the said sections a distance equal to the thickness of the top and bottom and the braces 18 secured 30 thereon. The braces on the top and bottom sections are coextensive with the width of those sections, and when the box is in set up or assembled position it is obvious that the ends of the various braces will abut. In 35 this manner the box sections will be relieved of strains when the box is roughly handled as the braces form a continuous band around the box. The arrangement also obviates injurious twisting action upon the box.

40 Upon properly arranging the various sections of the box, the nuts 17 may be applied to the various protruding stems 15, whereupon a rigid structure is provided. When it is desired to collapse or fold the 45 box to occupy small space the nuts may be quickly removed and the side 8 folded inwardly upon the bottom, the ends 9 and 10 are then folded inwardly upon the side 8, and the top 6 backwardly upon the side 7, 50 and the latter then folded under upon the bottom 5. The box is then in compact form and may be stored or packed in but a small

amount of space. The feature of the spaced hinge leaves permits of proper folding or nesting of the various sections.

55

It is apparent that a box constructed in accordance with the above description appeals particularly to those engaged in shipping or storing business, as the box when empty may be quickly and easily collapsed 60 and in this condition can be stored in but little space. The simplicity of the box is another particular advantage as the same may be manufactured at but small cost, and can be assembled and collapsed by anyone 65 and without the use of special instruments. It is obvious also that the uses to which the box may be adapted are numerous, and while in the present instance I have illustrated and described what appears to me 70 to be the most practical form of the box, it is to be understood that I do not limit myself to the construction set forth, but may make such minor changes in the arrangement of the various parts as I may deem 75 necessary without departing from the spirit of my claim.

Having described my invention, what is claimed is:—

A foldable box or the like embodying a 80 bottom, side walls hingedly connected thereto, end walls hingedly connected to one of said side walls, a top hingedly connected to the other of said side walls, spaced transversely disposed reinforcing elements 85 secured to each of the side walls, said reinforcing elements projecting above and below the upper and lower edges of said walls and having their lower extremities engaging the opposed longitudinal edges of 90 the bottom, and said top when in position being arranged between the upper extremities of said reinforcing elements, threaded bolts secured to the ends of the box, the bolts on each end being arranged in right 95 angular relation and extending beyond two adjacent edges thereof to project through openings in one side and the top of the box, and nuts on said bolts for holding the component parts of the box in assembled position.

In testimony whereof I affix my signature.

THOMAS BEASLEY.
